US0D1108428S

(12) **United States Design Patent** (10) **Patent No.:** **US D1,108,428 S**
(45) **Date of Patent:** **** Jan. 6, 2026**

(54) **MONITOR**

- (71) Applicant: **SAMSUNG ELECTRONICS CO., LTD.**, Suwon-si (KR)
- (72) Inventors: **Pilkwon Jung**, Suwon-si (KR); **Daehee Yoon**, Suwon-si (KR); **Taeyeon Won**, Suwon-si (KR); **Wonchul Hwang**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/937,251**
- (22) Filed: **Apr. 12, 2024**

(30) **Foreign Application Priority Data**

- Oct. 25, 2023 (KR) 30-2023-0041793
- (51) **LOC (15) Cl.** **14-02**
- (52) **U.S. Cl.** **USPC** **D14/375**
- (58) **Field of Classification Search**

(57) **CLAIM**

The ornamental design for a monitor, as shown and described.

DESCRIPTION

FIG. 1 is a front perspective view of a monitor, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines illustrating portions of the monitor form no part of the claimed design.

1 Claim, 8 Drawing Sheets
